UNITED STATES PATENT OFFICE.

IGNATIUS TRAVERSARO, OF SAN FRANCISCO, CALIFORNIA.

ATTACHMENT FOR PIANOS.

1,144,512.

Specification of Letters Patent. Patented June 29, 1915.

Application filed September 3, 1913. Serial No. 787,882.

To all whom it may concern:

Be it known that I, IGNATIUS TRAVERSARO, a citizen of the United States, residing at No. 3334 Mission street, San Francisco, in the county of San Francisco and State of California, have invented certain new and useful Improvements in Attachments for Pianos, of which the following is a specification.

10 The present invention relates to an improved combination piano of simple construction, having combined therein exposed mechanism in the form of an accordion and suitable reed mechanism employed in accordions of the well known type, both of which are operated on the actuation of the piano keys, one to effectually produce the music similar to that produced by an accordion and one to present to the mind of the observer the operation of an accordion bellows and keys in combination with the playing of the piano. The operation of the accordion bellows and keys creates an illusion in the mind of the observer and increases the attention and interest in the operation of the device.

The invention has for its principal objects to provide a structure of the above mentioned type which is capable of incorporation within upright pianos, in the space adjacent the piano hammers and the front board, one in which the operation of the accordion bellows and keys will be visible through a suitable open panel in the front board, thereby creating an interest in the operation of the instrument, and one which is simple in construction, is composed of but few parts and is mounted in the piano so as to be readily removed therefrom for repairing, should any of its mechanism become deranged.

With the above mentioned and other objects in view, the invention consists in the novel construction and combination of parts hereinabove described, illustrated in the accompanying drawings, and pointed out in the claims hereto appended; it being understood that various changes in the form, proportion, size, and minor details of construction, within the scope of the appended claims, may be resorted to without departing from the spirit or sacrificing any of the advantages of the invention.

To more fully comprehend the invention, attention is directed to the accompanying

drawings forming a part of this specification, and in which—

Figure 1 is a view in elevation of the upper portion of an upright piano with the front board removed therefrom, disclosing my improved attachment in position and a portion of the mechanism for operating the same. Fig. 2 is an enlarged front elevation partly in section of my attachment, disclosing the wind chest, the pumping and equalizing bellows and the accordion keys. Fig. 3 is a vertical sectional view of the upper portion of a piano with my device mounted therein, disclosing more fully the accordion bellows and keys, and the glass panel in the front board, through which the operation of the keys and bellows may be seen. Fig. 4 is a transverse sectional view of the wind chest and reed box, disclosing the reeds, the valves for controlling the passage of the air therethrough, the accordion buttons, and the connection between the valves and the buttons. Fig. 5 is a top plan view of Fig. 4.

Referring more particularly to the drawings, wherein like characters of reference designate corresponding parts throughout the several views, 1 indicates the upper portion of a piano casing of the upright type, provided with the action 2 of any well known type, the strings 3, sounding board 4, and removable front board 5, which is formed with a transparent panel 6, through which may be viewed my attachment hereinafter more fully described.

The frame of my attachment consists of the upper transverse member 7, provided at each end with the plates 8, which rest on the upper portion of the casing side members immediately below the top 9, and extending downwardly from the member 7 are the spaced vertical standards 10, provided adjacent their lower ends with the angle plates 11, which are detachably secured to the piano casing as in Fig. 3. Suitable cross members 12, 13, and 14 connect the standards 10 at their rear edges. Secured to the underside of the member 7 between the standards 10 are the pumping bellows 15, each provided with the valve controlled inlet and exhaust openings 16 and 17, and the movable leaves 18 of said bellows are alternately operated by the arm 19, pivoted at its center to a stationary support as at 20, and slidably connected adjacent its ends between the leaves 18 and brackets 21. The

arm 19 receives its power through a link 22, pivotally connected thereto and to a pulley 23 rotatably mounted in a bracket 24 carried by one of the standards 10, and said pulley 5 is driven by a belt 25 extending around a pulley 26 which is connected to a pulley 27, driven by a belt 28, which in turn receives its power from any suitable source, the pulleys 26 and 27 being supported by a bracket 10 29 secured to the inner end wall of the piano casing.

An equalizing bellows 30, retained in its expanded position by the spring 31, is mounted on the underside of the transverse member 7 above the belt and pulley mechanism, and said bellows is connected through a passage or channel 32 with the valve controlled inlet openings 16 of the pumping bellows 15. A channel or passage 33 connects 15 the equalizing bellows 30 with one end of a wind chest 34, supported by the standards 10 below the pumping bellows 15, and in said wind chest is mounted a reed box 35 provided on its interior with a plurality of 20 sets of reed cells 36, in which are mounted the reeds 37, each set being tuned to correspond with the piano key note with which 25 they are associated.

Associated with the sets of reed cells 36 30 are air inlet openings 38, which are controlled by valves 39 carried by supporting arms 40, pivotally mounted as at 41, and said valves are retained in position to close said openings 38 by springs 42. The opposite 35 ends of the arms 40 are bent upwardly as at 43 and extend through suitable eyes 44 formed in the ends of the arms 45 attached to the accordion keys 46, which are slidably mounted in openings 47 in the key board 48, 40 positioned between the pumping bellows 15 and the valves 39, and exposed to view through the panel 6.

The respective valves are operated by the pitmen or lifters 49 which operate in the 45 guides 50 and extend at their upper ends through the reed box and rest at their lower ends on the piano keys 51, as in Fig. 2 of the drawings.

Suspended from the lower forward edge 50 of the wind chest 34, and visible through the transparent panel 6 is an imitation accordion type of bellows 52, carrying at its lower edge a stay member 53, to which is pivotally mounted, as at 54, an operating arm 55 which is pivoted at one end as at 56 to one of the vertical members 10, and is connected at its opposite end by a link 57, with the free end of the arm 19. It will be observed that on the operation of the arm 19 to actuate the 60 pumping bellows, that the accordion bellows will also be operated, and that on the operation of a piano key, the reed cell associated therewith will be opened and the movement of the valve controlling the reed cell will 65 cause the operation of the accordion button

or key associated therewith, thereby producing the operation of an imitation accordion in conjunction with the operation of the piano and presenting an illusion to the mind of the observer which will create an interest 70 in the operation of the apparatus.

The operation of the device is as follows:—When the piano is operated, preferably from the same source of power that operates the bellows, the air suction bellows will be alternately operated and will 75 create a suction in the wind chest, through the channels 32 and 33, and equalizing bellows 30. The operating of the air suction bellows will also cause the accordion bellows to be operated. As a piano key is operated, the valve 39 associated with the pitman 49 is raised, permitting air to be drawn in that portion of the reed box controlled thereby, through the reed cells, and a sound similar 80 to an accordion note is produced simultaneously with the note produced by the striking of the piano hammer against the piano wire. The actuation of the valve will cause the accordion key or button associated therewith to be drawn inwardly; thus by the employment of my improved apparatus the 85 music and effect of the operation of an accordion are produced in combination with the playing of a piano, and the attention 90 and interest of the observer will be increased, as an illusion will be created as to the operation and control of the reed mechanism by the accordion bellows and keys.

My improved device is preferably employed in connection with the melody, beginning with C sharp and including high G, in all thirty-one keys.

For convenience in handling, I preferably construct the transverse member in three sections, hinging the two end sections to the central one by suitable hinges 57, as disclosed in Fig. 1.

It will be apparent from the above description and accompanying drawings that my improved attachment is positioned in a piano between the hammers and front board thereof, thus occupying a space which at the present time is not used, and it will also be apparent that by positioning the wind chest, accordion keys, and accordion bellows immediately in rear of the glass panel that the operation of the accordion keys and bellows will be visible exteriorly of the instrument casing.

Having thus described my invention, what I claim as new and desire to protect by Letters Patent is:—

1. In an attachment for pianos and in combination with the case, a casing front board provided with a transparent panel, an air suction device, a reed box, a wind chest connected with said air suction device, an imitation accordion bellows in rear of said transparent panel and visible through 130

the same, means for operating said bellows, mechanism for opening communication from said wind chest into said reed box and for admitting air to be drawn through said reeds, 5 a plurality of accordion keys in rear of said transparent panel and visible through the same and means for operating certain of said keys.

2. In an attachment for pianos and in 10 combination with the case, a casing front board provided with a transparent panel, an air suction device, a wind chest, a reed box positioned in said wind chest and provided with reed cells and reeds, an air passage between said wind chest and said air 15 suction device, an imitation accordion bellows visible through said transparent panel

and said bellows being connected to and operated by the actuation of said air suction device, valves for admitting air to be 20 drawn through said reeds into said wind chest, and a plurality of accordion keys visible through said transparent panel and each of said keys associated with and operated by the operation of certain of said 25 valves.

In testimony whereof I have signed my name to this specification in the presence of two subscribing witnesses.

IGNATIUS TRAVERSARO.
